ASH-RECEPTACLE COMPACT

Abraham D. Kaner, Webster Groves, Mo.

Application January 28, 1938, Serial No. 187,401

2 Claims. (Cl. 131—242)

This invention relates to improvements in ash receptacles, for disposing of the ashes from cigarettes and the like, and fragments of the cigarettes themselves, and more specifically to a receptacle which may be carried conveniently on the person, 5 as in a pocket or purse, or even in the hand, and which will be substantially in the form and shape of a compact or the like so as to be neither unsightly nor burdensome.

10 The invention has among its objects the production of an ash-receptacle compact of the kind described, which will be extremely neat and attractive in appearance, simple in construction, small enough to be conveniently retained in a 15 pocket or a purse while not in use and easily held in the hand while in use, and which will be otherwise satisfactory and efficient for use wherever deemed applicable.

One of the objects of my invention is to so construct said device that it will not only receive and hold the ashes, but will also support the cigarette from time to time when the latter is not actually being held nor being smoked, but is merely placed aside for a short interval in the usual manner.

25 Another object of my invention is to provide a device of the kind described, having the cigarette holder thereon, and in which said holder is especially constructed as to be movable into the ash compartment itself when the compact is closed, 30 and said holder being so positioned that when a lighted cigarette is placed thereon, the ashes will tend to fall into the ash compartment of the device.

A further object of my invention is to so construct the cigarette holder that it will cooperate with the opening and closing movement of the compact itself, and wherein the holder will automatically move to cigarette-holding position when the compact is opened, and will be moved to inoperative or folded position within the compact 40 when the compact is closed.

Many other objects and advantages of the construction herein shown and described will be obvious to those skilled in the art to which this 45 invention appertains, from the disclosures herein given.

To this end my invention consists in the novel construction, arrangement and combination of parts herein shown and described, and the uses mentioned, as will be more clearly pointed out in the claims hereunto appended.

In the drawing, wherein like reference characters indicate like or corresponding parts 55 throughout the views,

Figure 1 is a perspective view of the device in normal operative position;

Figure 2 is a cross-sectional view through the same, showing several stages of closure movement; and

Figure 3 is a perspective view of a detail of construction showing the holder and spring support therefor.

Referring more particularly to the drawing, wherein I have illustrated a preferred embodiment of my invention, there is shown a receptacle in the general form, shape and size, of the well-known compacts generally carried by women, or to small cases of various sorts carried by men.

In the form shown, the receptacle consists of a 15 base or container portion or part 1, and a cover 2 preferably hinged thereto, the well or ash-receiving and holding opening being indicated at 3.

The part 1 may be provided with a flange 4 extending downwardly from the top edge of said 20 part, and thence projecting radially inwardly either entirely about the lower periphery of said flange as at 5, or at only a limited portion of said periphery, so as to provide a securement for the lowermost end of the cigarette-holder support as 25 will be presently described.

Obviously, the device as thus far set forth will be useful for receiving and retaining portions of ashes and fragments of cigarettes therein, being held in the hand while smoking, or placed on any 30 near-by supporting surface, such as a table, chair, mantle, etc., as found most convenient, and hence will be ready for the use to which it is adapted.

If desired, the compact may be lined or interlined with some heat-insulation such as asbestos 35 6, and the compact may be made of any desired material and ornamented in any manner, thus preserving its neatness and beauty without destroying any of its utility.

However, in order to increase its utility, I have 40 provided a cigarette-holder or rest 7, of such length that it may be readily received within the opening 3, so that the cigarette may be placed on said holder from time to time in the usual manner. In order that there will be no tendency for the 45 ashes from the cigarette on the holder 7 to drop beyond the ash-receptacle, I prefer to position said holder so that it lies substantially in a plane at a slight angle to the horizontal plane, the cigarette being indicated at 8 thereon. The holder may be 50 in the form of a trough in transverse cross-section.

Although the holder may be mounted so as to be moved manually into operative position for supporting the cigarette thereon, I have found it 55

preferable to so construct its mounting that the opening movement of the cover of the compact will shift the holder to normal or operative position, while the closing movement of said cover will 5 actuate the holder to its inoperative position so as to lie within the confines of the opening 3. If there are any fragments of the cigarette within the opening, the holder will tend to compress them and hold them in the space within the receptacle, so that a larger quantity can be stored therein than where the fragments are freely movable within the receptacle.

A length of spring wire may be formed into the pair of legs 9-9, there being a bight 10 provided intermediate the ends of said length of wire, the ends of said legs being provided with coils 11-11 and with a short length of wire 12 projecting therebeyond. When said portions 12-12 are held fixed to some portion of the part 1, as for example to the radially extending projection 5, and the main part of said spring wire support is deflected from its normal substantially upright position, to downwardly and inwardly of the opening 3, the support will tend to retrieve itself to its original or upright position as soon as the pressure or force holding it downwardly is released, the coils 11-11 assisting in this retrieving movement, of course.

The holder is provided with prongs 13-13 to receive the pair of spring wires at the portions 14-14 adjacent to and rearwardly of the bight, and to be clamped thereabout, and in order to further prevent undesired shifting relatively between these portions, said bight may be widened out or spread as indicated so as to provide an abutment stop against said prongs.

Each of the legs of the spring support is preferably provided with several spring coils 15 closely adjacent the point of securement of the prong to said wire, and the wires are given such a bend 40 at said coils 15-15 that when the coils 15-15 are not compressed or put into torsion, the upper portion of said support will substantially lie in a plane at an angle to or offset from the plane in which the lower or main portion of said support lies. In other words, the object of this offset is to position the bight end of the support at a lower elevation than the coils 15-15, and whereby the holder 7 will lie in a plane to correspond with this difference in elevation and in 45 consequence extend obliquely to the horizontal plane. In this manner, when the support is in its normal operative position, the holder will have its innermost end lower than its outermost end, the angle being such that it will not be unduly steep and cause a cigarette to slide off the same by gravity alone.

The holder and support thus constructed will automatically be shifted to normal operative position when the cover is out of contact therewith, but will be shifted to inoperative position with the closing movement of the cover, as will now be described.

Assuming that the parts are in the position shown in Fig. 1, and it is desired to take the device out of service until again needed. The simple movement of closure will force the cover against the outermost edge of the cigarette holder, and the continued movement in the same direction will shift said edge about the coils 15-15 as a pivot and finally bring said edge forwardly in advance of the other edge of the holder, this movement being against the torsional force of 10 said coils. The continued movement of closing will cause said cover to engage and transmit the closing force to various parts of the holder and spring support to finally actuate the same to the position immediately subsequent to that indicated in the full lines in Fig. 2, the other stages of movement being indicated in dotted lines in said figure.

The cover latches shut at the termination of closure movement, and as soon as this latch is 20 released, the cover may be moved to open position, and the coil springs 11-11 and 15-15 will exert their force to bring the support to its upright position and to tilt the holder to said normal position.

The ashes may be emptied from time to time, and the interior of the compact cleaned out by wiping, washing or the like.

What I claim as new and desire to secure by Letters Patent is:

1. In an ash receptacle, an ash container; a cover movably connected to the same; a cigarette-supporting trough; a trough support pivoted to said container for movably mounting said trough to project an end of the latter into 35 cover engaging position when said cover is in opened position; and spring means for normally holding said support in operative position to permit the trough to support a cigarette, and yieldably resisting movement of the support to inoperative position, and whereby the closing movement of said cover causes the latter to engage with and overturn said trough to its inoperative position.

2. In an ash receptacle, an ash container; a 45 cover movably connected thereto; a cigarette-supporting trough for supporting a cigarette along its length thereon; a support for said trough and pivoted to said container for movably mounting said trough on said container so as to project an end of the trough into the path 50 of movement of the cover when the latter is in opened position; and spring means cooperating with said support whereby overturning movement of said trough is yieldably resisted and 55 whereby movement of said support to inoperative position is yieldably resisted, the closing movement of said cover actuating the latter into engagement with the trough and overturning it to inoperative position.

60

ABRAHAM D. KANER.
